UNITED STATES PATENT OFFICE.

JOSEPH A. MEYER AND JOSEPH S. SATTER, OF ROCHESTER, NEW YORK.

DOOR.

No. 823,065.

Specification of Letters Patent.

Patented June 12, 1906.

Application filed November 8, 1905. Serial No. 286,407.

To all whom it may concern:

Be it known that we, JOSEPH A. MEYER and JOSEPH S. SATTER, of Rochester, in the county of Monroe and State of New York, have invented a new and useful Improvement in Doors, which improvement is fully set forth in the following specification and shown in the accompanying drawings.

Our invention is an improved door for conveniently closing doorways or openings leading into apartments or inclosures generally, it being designed more particularly to be used to close the doorways of refrigerator-cars. Doors for this purpose need to close the associated openings tightly, making airtight joints all round, which cannot be conveniently effected with an ordinary sliding door, and the hinged door in common use is clumsy and further objectionable, as when swinging out from the side of the car it is much in the way and a source of danger, especially when passing through tunnels.

We have aimed in our present invention to improve upon the doors now in use upon the sides of refrigerator and other freight or box cars.

The objects and advantages of the invention will be brought out and made to appear in the following specification and the construction particularly pointed out in the appended claims, reference being had to the accompanying drawings, which, with the reference characters marked thereon, form a part of this specification.

Figure 1 is a side elevation of a part of the wall of a car or other inclosure, showing our improved door in place thereon, parts being shown in two positions by full and by dotted lines, with parts broken away. Fig. 2 is a horizontal section of parts, taken on the broken dotted line 2 2 in Fig. 1, parts being shown in two positions by full and by dotted lines. Fig. 3 is a vertical section on the dotted lines 3 3 in Figs. 1 and 2, parts being broken away. Fig. 4 is a front elevation of a part of the door, more fully showing in detail the form and arrangement of parts, parts being broken away and omitted. Fig. 5 is a vertical section of parts of the door and associated parts on the dotted line 5 5 in Fig. 4, parts being broken away. Fig. 6 is a plan of a carrying-arm and some associated parts seen as in Fig. 2. Fig. 7 is a plan of some of the parts shown in Fig. 6 occupying different relative positions. Fig. 8 is a horizontal section of a part of the door and some associated

parts, taken on the dotted line 8 in Fig. 1, parts being broken away. Fig. 9 is a side elevation of some of the mechanism supporting the door, seen as indicated by arrow 9 in Fig. 6, parts being broken away. Figs. 6 to 9, inclusive, are drawn to a scale twice that of the other figures.

Referring to the parts shown in the drawings, A, Figs. 1, 2, and 3, represents a portion of a wall of an inclosure, as the side of a freight or refrigerator car. B is an opening or doorway through the wall or side A, and C our improved door to fill and close the opening B. The door C is supported and controlled by means involving upper and lower trucks or carriages D, having grooved wheels a adapted to roll upon and along horizontal tracks E E, secured to and parallel with the wall A and equidistant therefrom, said tracks being respectively above and below the opening B, as shown. The trucks D D comprise each a pair of equal short vertical posts or standards b b, the two standards of the lower truck being in vertical lines beneath the two standards of the upper truck. These standards are a short distance outside of the two tracks E E and carry or hold the wheels a, as shown.

The door C is provided with a series of four vertical brackets d in upper and lower pairs, the brackets of the upper pair projecting slightly above the upper edge of the door and those of the lower pair projecting similarly below the lower edge of the door. These brackets are each formed with a laterally-expanded part or head c, Figs. 1, 3, and 9, at its projecting end, each head having a longitudinally-projecting center pin e, the pins of the upper brackets pointing vertically upward and those of the lower brackets pointing vertically downward. Likewise the standards b are formed with longitudinally-projecting pins f, Figs. 1, 3, 6, and 9, similar to the center pins e, the pins of the two upper standards being at the lower ends of the latter and pointing downward and those of the lower standards being at their upper ends and pointing upward. The standards b and the lugs d occupy such relative positions that the four pins e f above the door are in a horizontal plane, likewise the four pins below the door, all the pins being connected in pairs by carrying-arms g, Figs. 1, 2, 3, 6, and 9. These carrying-arms are all of the same length and alike, each being pivotally connected with the parts at either end, which admits of the

door being swung sidewise bodily in a horizontal direction from its place in the doorway B, Fig. 2, to the position shown by dotted lines to open the car or in the reverse direction to close the car, as the case may be.

The heads of the lugs *d* are each further formed with a projecting stud *h* at its outer edge, Figs. 6, 7, and 9, the adjacent circular heads of the carrying-arms *g* having peripheral recesses *i* to make way for the respective studs *h*, so the said arms may freely turn on the respective center pins *e* when the door is swung, as above stated. The parts or shoulders *k* of the arms terminating the left ends of the respective recesses *i* meeting the adjacent studs *h* constitute collectively a stop for the swinging or circular motion of the door C when moving outward from the opening B, holding it in the position indicated by dotted lines in Fig. 2. When thus swung outward to open the car, the door is in position to be rolled or moved laterally along the tracks E E to the position shown by full lines in the figure, all positions of the door being parallel with one another and with the side of the car or wall A. The length of the carrying-arms *g* is such and the stop-stud *h* so relatively placed that the door can in no case move far from the adjacent part of the car, its extreme or outermost position (shown in Figs. 2 and 3) being only sufficient to admit of its moving freely edgewise along the tracks without touching the side of the car. The edgewise motions of the door are made parallel with the side of the car, stops *g'*, Fig. 1, on the tracks being provided to arrest the lateral motions of the door in both directions. Fig. 6 shows clearly the shoulder *k* in contact with the stud *h*, as when the door is swung outward, as stated, the relative positions of the door and the adjacent part of the carrying-arm when the door is closed being shown in Fig. 7, the stud being at the opposite end of the recess *i*.

The opening or doorway B is preferably made with flaring sides, as appears in Figs. 1 and 2, covered with yielding or fibrous strips *l* for packing, the edges of the door C being similarly slanted at *m*, where meeting the said fibrous strips. The door is further formed with rectangular outer and inner parts *n o*, Figs. 2, 3, 6, and 8, to fill correspondingly-formed portions *p r* of the opening B, altogether the door C when in place forming an air-tight joint with the four sides of the opening.

The door C is held in place in its closed position and controlled by mechanism involving a series of latch-bolts *s*, Figs. 1, 2, 3, and 8, catching under rests or sockets *t*, secured to the side or wall A adjacent to the respective sides of the opening B. At the middle of the door is placed a short horizontal headed spindle *u*, (shown more in detail in Figs. 4 and 5,) projecting from the door and adapted

to turn in a sleeve *v* rigid with the door. The outer end of this spindle is squared for a distance for receiving upon it a star-piece or multiple-armed part *w*, holding pivotally at the ends of its branches the inner ends of the respective latch-bolts *s*, as appears in Fig. 1. Outside of the part *w* is placed a jointed lever *x*, Figs. 1, 2, 3, and 5, made rigid with the spindle *u*, by means of which the latter, with the part *w*, is turned for the purpose of moving the series of latch-bolts into engagement with their respective sockets *t* or away therefrom, as clearly indicated by the full-line and the dotted-line positions of the parts shown in Fig. 1. The side motion of the lever *x* for withdrawing the latch-bolts from the sockets is arrested by a stop *y* rigid with the door, the movements of the latch-bolts being controlled by loops *z* rigid with the door.

The lever *x* consists of two main parts joined by a hinge *a'*, Figs. 1 and 3, the extreme part *b'* having an opening *c'* to pass over and receive a stud *d'*, Figs. 1 and 2, reaching outward from the surface of the door C to hold the lever. This catching of the lever by the stud *d'* serves to lock it in position to hold the latch-bolts *s* in engagement with the sockets *t*, thus holding the door securely closed.

We provide with the other parts a curved catch-finger *e'* upon the lever *x*, pivoted to the latter in position to have its free end pass through an opening in the stud *d'* outside of the lever to prevent the escape of the latter from the stud *d'* until the catch-finger is withdrawn from the stud. The extreme end of the catch-finger is perforated, as shown at *e''*, or otherwise roughened to hold a body of wax for sealing the door.

To cause the door to be firmly pressed to place when closed, the free ends *f'*, Figs. 2 and 8, of the latch-bolts *s* are tapered, as shown, the adjacent surfaces of the sockets *t* being correspondingly inclined. This form of the engaging parts causes the door when closed and secured to firmly press the packing-strips *l* and form an air-tight joint with the car all round.

To open the car or inclosure, the seal is first broken from the end of the catch-finger *e'* and the latter turned back out of the stud *d'*. The outer part *b'* of the lever is then turned upon the hinge *a'* away from the stud to release the lever, which may be then swung laterally to the position shown by dotted lines in Fig. 1, which withdraws the latch-bolts from the sockets and allows the door to be swung on the trucks D back from the side or body A, when the door may be readily rolled to the right away from the opening B, as stated. To again close the car, the door is returned to the left—to the position shown by dotted lines—when it may be again swung into place in the opening B, these rectilinear rolling motions and the

swinging or circular motions being distinct from each other and alternated.

What we claim as our invention, and desire to secure by Letters Patent, is—

- 5 1. The combination of a door, upper and lower tracks, upper and lower trucks having wheels running on said tracks, carrying-arms pivotally connected at one end to the standards of said trucks, the other ends of said arms being formed with circular heads having peripheral recesses and shoulders, vertically-disposed brackets on the door at top and bottom and projecting beyond the top and bottom edges of the door, each bracket having a laterally-expanded part at its projecting end with a vertically-projecting stud and an integral vertically-disposed center pin, said pins being engaged in openings in the ends of the carrying-arms and said studs disposed in said peripheral recesses and engaging said shoulders, and oppositely-disposed stops on opposite ends of the tracks, one for engagement with a wheel of the truck 40 and the other for engagement with a standard of the truck for limiting the movement of the door.
- 10 15 20 25 2. The combination of a door, upper and lower tracks, upper and lower trucks having wheels running on said tracks, carrying-arms pivotally connected at one end to the standards of said trucks, the other ends of said

arms being formed with circular heads having peripheral recesses and shoulders, vertically-disposed brackets on the door at top and bottom and projecting beyond the top 30 and bottom edges of the door, each bracket having a laterally-expanded part at its projecting end with a vertically-projecting stud and an integral vertically-disposed center pin, said pins being engaged in openings in 35 the ends of the carrying-arms and said studs disposed in said peripheral recesses and engaging said shoulders, and oppositely-disposed stops on opposite ends of the tracks, one for engagement with a wheel of the truck 40 and the other for engagement with a standard of the truck for limiting the movement of the door.

In witness whereof we have hereunto set our hands, this 4th day of November, 1905, in 45 the presence of two subscribing witnesses.
